UNITED STATES PATENT OFFICE.

AUGUSTUS PETER KOCH, OF NEW YORK, N. Y.

AIRSHIP.

1,207,934.

Specification of Letters Patent. Patented Dec. 12, 1916.

Application filed March 28, 1914. Serial No. 828,040.

To all whom it may concern:

Be it known that I, AUGUSTUS P. KOCH, a citizen of the United States, and resident of the borough of Manhattan, city, county, and State of New York, have invented certain new and useful Improvements in Airships, of which the following is a specification.

This invention relates to a type of air ship which is a combination between a dirigible and an aeroplane, in that it has an extended body adopted to receive and retain a buoyant gas in sufficient quantities to support all of the dead or permanent weight of the machine and attached thereto a plurality of extended wings which coöperate with high speed propellers in producing an aeroplane action sufficient to support the weight of the fuel, oils, and other commodities together with the weight of the operator and passengers. By this combination I believe that it is possible to produce a machine adapted for long and continuous trips at exceedingly high speed.

I have also arranged other features of importance and novelty which together with the details of construction and the method of operation will be fully described as the specification progresses.

The following is what I consider the best means for carrying out this invention.

The accompanying drawings form a part of this specification, in which—

Figure 1 is a bottom plan view and, Fig. 2 is a side elevation.

Similar reference numerals indicate like parts in all the figures where they appear.

In the preamble I have set forth that my invention consisted of a body built in the manner of a dirigible having a balloon body of elongated plan adapted to contain a buoyant gas. This body is indicated at 1 and the upper portion is straight and full gradually tapered toward each end. Another of the principles of my construction is the provision within the outline of the body, of a space sufficient to receive the engines, the aviators, and passengers together with such commodities as it may be desirable to carry. This space is arranged at the forward end of the body at the lower side thereof. It has virtually three separate compartments, the forward compartment 2, being of a sufficient height to allow the operator to stand upright or sit in a comfortable position. The second compartment, 3 is a passage way, and the third compartment, 4 provides sufficient

room for the engines. So as to obtain a maximum supporting and gas containing space, I provide that the body shall be of a peculiar shape. Above the compartments 60 the body of the dirigible in plan is what is termed cigar shaped, the ends being pointed as fully shown in Fig. 1. In elevation, however, the ends of the body of the dirigible are squared off the rear for the accommodation 65 of a steering rudder 5, and the forward end for the purpose of providing for the compartments as described.

It will be noted that I have provided two engines 6 and 7 of the high speed rotary type 70 and I so connect my engines that they may operate together or independently of each other. Immediately over the engines I have arranged three tanks as shown at 8, 9 and 10, tanks 8 and 10 which may be of liberal 75 area, contain the gasoline or other hydrocarbon fuel and the intermediate tank 9, which is smaller in capacity will contain the lubricating oil.

Secured to and operated by each engine 80 are the propellers 11 and 12 and although the greater portion of these propellers operate within the outline of the body, I have arranged that the air agitated by the propellers shall not be confined and for that 85 purpose I have tapered that portion of the dirigible body immediately behind the propellers in the manner as indicated at 13 and 14.

Greater supporting planes of my device 90 are over the engine compartment and are shown at 15 and 16. The forward end of each of these planes is capable of an up and down movement to assist in raising the whole device and to obtain this peculiar 95 movement of the wings I pivot each of the wings as shown at 17 and 18 and connect them together by means of a bar, 19. This bar is journaled in the end of a rod 21 which pivoted to the front end of the body as shown 100 at 20, as by these means I obtain the greatest rigidity. I connect flexible cables or chains one to a rod 21 and the other to a vertical bar which connects the rod 21 with the wings and I pass these chains or cables over a hand wheel 22. The rotation of the hand wheel will lift or depress the bar 21 and elevate or depress the forward ends of the wings 15 and 16. It will be noted that I have arranged another series of wings adjacent to the back end of the body as shown at 105 23 and 24. These wings are of smaller di-

ameter and may or may not be hinged at 25 and 26. If hinged, I will provide a means for elevating or depressing the outer edge, 27 and 28 of each of the wings. These 5 means will consist of a cable 29, connected with each of the wings and terminating in a lever 30 in the operating chamber. I may provide 2 levers so that the wings may be operated separately and thus materially assist 10 the rudder in the performance of its duties.

The rudder, 5 is provided with a double tiller rope 32. The ends of each will pass around a drum 33 in the operating chamber, 15 which drum is rotated by the hand wheel 34. The operation of this rudder is well understood, though I have found in a ship as large as that of my construction the rudder must be of liberal area.

20 At 35 and 36 I have shown a landing gear sometimes called a chassis. This gear may be of any preferred construction but it is my intention that it be constructed of 6 wheels, 3 upon each transverse shaft. It is obvious 25 that this landing gear shall be secured to a portion of the body well adapted to withstand the strain of its operation.

In constructing my ship, I prefer to employ ash or hickory well seasoned for the 30 ribs and keel covering the whole of the dirigible body with a thin but exceedingly strong three ply veneer, that has been treated in a manner that will make it airtight and impervious to moisture, and although it has been my intention to construct 35 the planes of the same light and strong wood, I believe that fabric planes may operate as satisfactorily. I have also arranged

to employ two rotary engines of about 140 H. P. each, but it will be understood that 40 the size of the machine, the size of the engines and any of the portions of the general construction may be changed at will. It will be also understood that modifications may be made within the scope of the appended claims without departing from the principle or sacrificing the advantages of 45 the invention.

Having carefully and fully described my invention what I claim and desire to secure by Letters Patent is:

1. A device of the character described comprising a body oval and tapered in plan, and oval and blunt in elevation, said body being adapted to contain a buoyant gas and 55 being shaped to provide a plurality of chambers for the operating means and the operator, and an upwardly projecting portion over said chambers to provide gas containing space throughout the entire body as herein 60 specified.

2. A combination of a dirigible and aeroplane comprising a body adapted to retain a buoyant gas and having its forward end extending upwardly above the plane of the 65 upper surface of the remainder of the body, pivoted, elevating wings at the forward end of said body and hinged wings at the rear end, and a rudder all combined for the purpose set forth.

Signed at the city of New York, State of New York, this 19th day of March, 1914.

AUGUSTUS PETER KOCH.
